UNITED STATES PATENT OFFICE

166,292

ROTATABLE CONTROL KNOB

Howard Edward Anthony, Benton Harbor, Mich.,
assignor to Heath Company, Benton Harbor,
Mich., a corporation of Michigan

Application October 23, 1951, Serial No. 17,085

Term of patent 14 years

(Cl. D26—13)

To all whom it may concern:

Be it known that I, Howard E. Anthony, a citizen of the United States, residing at Benton Harbor, county of Berrien, and State of Michigan, have invented a new, original, and ornamental Design for a Rotatable Control Knob, of which the following is a specification, reference being had to the accompanying drawing, forming a part thereof, in which:

Figure 1 is a top plan view of a rotatable control knob embodying the ornamental design of my invention;

Figure 2 is an end elevation looking from the left of Figure 1;

Figure 3 is a side elevation;

Figure 4 is an end elevation looking from the right of Figure 1, and

Figure 5 is a bottom plan view.

I claim:

The ornamental design for a rotatable control knob, as shown.

HOWARD EDWARD ANTHONY.
